UNITED STATES PATENT OFFICE.

HAROLD S. RAMBO, OF NEW YORK, N. Y.

PAINT MIXER.

Application filed December 5, 1928. Serial No. 323,992.

This invention relates to a mixing or stirring device.

The principal object of the invention is the provision of a device designed and adapted for quickly and thoroughly stirring or remixing ready-mixed paint or other paint products, which, by reason of standing for a long time have settled.

The nature of the invention and its distinguishing features and advantages will appear when the following specification is read in connection with the accompanying drawing, in which—

Figure 1 is a vertical sectional view of a paint can with the cover removed and showing the mixing device of the present invention applied thereto.

Fig. 2 is a plan view of the can and the mixing device.

Referring now more particularly to the drawing it will be apparent that there has been shown a receptacle or can 10 of the usual construction for containing ready-mixed paint or other paint products. The ready-mixed paint or other paint products which have been stored ready for sale, become settled after a certain period of time with the result that the pigment rests on the bottom of the can and requires remixing, stirring or agitation to put it in condition for use. To this end there has been provided a device presently to be described which is designed and adapted for quickly and thoroughly conditioning ready-mixed paint or other paint products which will be provided with each can of material, and which will be of durable and inexpensive construction.

The device will include means for attaching and supporting it to a can in operative position. The said means consists of a supporting member 11 having spring clips or clamps 12 respectively at the opposite ends of said member 11 which are detachably engageable with the rim on the upper end of the can. A mixer or stirrer 13 is associated with the supporting member 11 for vertical sliding movement and also for rotatory movement. The mixer 13 is constructed of a single piece of wire bent upon itself to

provide an arbor 14, crank handle 15, loops 16 and loops 17, and an agitator 18. The loops 16 and 17 constitute a stirring paddle. The loops 16 and 17 are disposed transversely with respect to the axis of the arbor 14. The arbor 14 extends through the member 11 and also through a bearing member 19 secured to the member 11 to give the proper stability to the mixer. The lowermost loop 17 rests on the bottom of the can and thus serves to properly support the mixer for rotatory movement. It will also be apparent that the mixer 13 is mounted for up and down movement as well as rotatory movement. The loops 17 are bent closely in order to give greater strength and rigidity to the paddle, inasmuch as the loops 17 are relied upon to overcome the greater inertia of the pigment at the bottom of the can when remixing the contents thereof. The agitator 18 which is vertically disposed to travel adjacent the side wall of the can 10 serves to overcome the effect of centrifugal force tending to retard a perfect mixture, by cooperating with the loops 16 and 17 to obtain a more perfect mixer. The mixture 13 may be moved up and down at will while being rotated for the purpose of thoroughly mixing the contents of the can, and being slidably mounted will also allow the device to operate in conjunction with cans of different depths.

I claim:

A mixing device comprising means adapted to detachably support it in operative position on a container, means rotatable on a vertical axis and constructed of a single wire to provide comparatively closely and widely bent loops constituting a paddle, said closely bent loops being lowermost to travel directly above the bottom of said container, an agitator positioned to travel adjacent the side wall of said container, and a crank handle for operating the paddle and agitator.

Signed at New York, in the county of New York, and State of New York, this 4 day of December, 1928.

HAROLD S. RAMBO.
